(57) **CLAIM**

The ornamental design for the straight opaque upper transparent lower flexible beverage container, as shown and described.

DESCRIPTION

Copyright notice: A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front perspective view of my design for a straight opaque upper transparent lower flexible beverage container showing the characteristic feature of the design, which resides in its shape together with having an opaque upper portion and a transparent lower portion.

FIG. 2 is a top view thereof.

FIG. 3 is a bottom view thereof.

FIG. 4 is a front elevational view thereof.

FIG. 5 is a right side elevational view thereof, the left side is identical; and,

FIG. 6 is a rear elevational view thereof.
